UNITED STATES PATENT OFFICE.

LEONARD H. DES ISLES, OF CAMBRIDGE, MASSACHUSETTS.

THERMOSTAT.

SPECIFICATION forming part of Letters Patent No. 740,254, dated September 29, 1903.

Application filed January 19, 1901. Serial No. 43,892. (No model.)

To all whom it may concern:

Be it known that I, LEONARD H. DES ISLES, a citizen of the United States, residing at Cambridge, in the county of Middlesex, State 5 of Massachusetts, have invented a certain new and useful Improvement in Thermostats, of which the following is a specification, reference being had therein to the accompanying drawings.

10 The invention relates to thermostats or thermally-operated instruments, and particularly to that class of thermostats wherein an electric circuit is made or broken, as the case may be, upon the occurrence of such an increase 15 in the temperature of the surrounding atmosphere as accompanies a fire.

More especially, the invention relates to the kind of thermostat in which the mechanism employed is held normally inactive by means 20 of a solder-joint and is caused to act by the melting of the solder. Some features of my device, however, are equally applicable to other forms of thermostat.

Commercial solder of a permanent character 25 melts at about 160° Fahrenheit; but hitherto it has been found impracticable to construct a thermostat depending for its operation upon a solder-joint which can be relied upon to act until the rising temperature has 30 considerably exceeded the melting-point of the solder. Other practical difficulties have been met in the construction of a thermostat, relating to economy of manufacture and the prevention of deterioration of the instrument 35 when in position a long while without being actuated.

The principal aim of the present invention is to produce a thermostat whose test-point 40 of action will closely approximate the minimum temperature named above.

Another object is to decrease the liability of the efficiency of the instrument being diminished or destroyed.

A further design is to protect the parts of 45 the instrument from access of moisture.

Other points of improvement will appear in the following paragraphs, and it will be obvious that several of these are applicable to electric alarms in general, whether or not 50 they are thermally operated.

The improvement will first be described in

connection with the accompanying drawings, which illustrate the best embodiment of the device thus far contrived, and afterward the features of the invention will be particularly 55 pointed out, and distinctly defined in the claims at the close of this specification.

In the drawings, Figure 1 is a plan view of the cap of the thermostat seen from the open back thereof. Fig. 2 is a section on the line 60 2 2 of Fig. 1 looking in the direction indicated by the arrows at the extremities of that line and showing the base-plate on which the cap is supported. Fig. 3 is a similar section on the line 3 3 of Fig. 1. Fig. 4 is a sectional 65 view of the assembled parts that are united by the solder-joint.

The terminals of the electric circuit in which the thermostat is placed are inclosed between a base-plate 1 and a cover 2, both of 70 these parts preferably being made of porcelain. The base-plate has an upturned rim 3, and the edge of the cover fits within this rim and makes contact with the inner surface of the base-plate. In order to attach the instrument to a fixed support, such as a wall or ceiling, screws 4 are employed. The base-plate is provided with circular projections 5, the ends of which abut against the cover. Holes are formed through the cover, projections, 75 and base-plate to receive the said screws. Rims or beads 6 are formed on the inner surface of the cover, surrounding the ends of the projections 5. By this construction it is insured that any moisture seeking escape along 80 the screws shall be prevented from reaching the working parts of the instrument.

Hollow plugs 7 are slipped upon the screws prior to the introduction of the latter into place, the screw-heads thus being caused to 90 remain elevated some little distance above the surface of the cover, whereby the central portion of the cover is protected when the thermostat is located in any exposed position of use, and consequently the heat-affected element of the instrument, which occupies such central position, is prevented from becoming injured. Co-operating with the screws 4 in this office are the binding-posts 8, which occupy intermediate positions 95 100 with relation to the screws.

Inasmuch as the thermostat is frequently

hung upon a free circuit-wire independently of a fixed support, it becomes desirable to attach together the base-plate and cover independently of their joint attachment to such fixed support, and for this purpose the binding-posts are utilized to furnish a bearing for such attachment, the shanks 10 of the binding-posts being extended through the base-plate and their extremities being screw-threaded and provided with nuts 12, which set in recesses 13 in the rear face of the base-plate. The binding-posts have squared enlargements 81 at the base of their shanks, which set in squared recesses 82 in the outer face of the cover. By this means the binding-posts are prevented from turning when the binding-screws are tightened and loosened, a contingency in which they would loosen the nuts 12 and permit of the separation of the cover from the base-plate.

One of the terminals of the circuit through the thermostat is a plate 9, through which passes the shank of the corresponding binding-post. In the operation of assembling the parts of the instrument a nut 11 is placed upon the said shank for the purpose of clamping the plate firmly to the cover. A portion 131 of the plate 9 is bent upward obliquely to afford a contact-surface for the second terminal. The second terminal is a blade-spring 14, connected with the second binding-post and clamped to the cover by a nut 15 on the shank of the binding-post in like manner to the plate 9. The spring 14, however, is not arranged in the customary manner—that is, extending directly across the space within the cover toward the plate 9—but starts outward and then doubles on itself and extends into proximity to the said plate. Thus there is obtained a very long spring which, because of its length, requires to be subjected to very little angular deflection in order to separate its extremity the required distance from the surface of the fixed terminal with which it coacts. A comparatively short spring like those commonly in use which is constantly maintained in a position of considerable deflection requires to be made of thin steel or some similar metal and is apt to rust in a moist atmosphere and become weakened or destroyed. A long spring, on the other hand, which is subject to only slight angular deflection, may be made of comparatively thick metal of a type possessing a moderate degree of resiliency and not likely to become rusted. I have obtained excellent results by constructing the spring in question of phosphor-bronze.

A coating 84 of non-corrodible material is applied to the contacting portion of the terminal 14, and a similar coating 85 is applied to the terminal 131 in order to insure a perfect contact being made when the instrument is caused to act. In practice these coatings are constituted of solder, which not only is non-corrodible, but operates to melt when the two terminals are brought together, the coat-

ings thereby fusing together and forming a perfectly continuous bridge from one terminal to the other. This will occur although particles of dust or other foreign matter should have lodged upon either of the terminals which in the ordinary construction would prevent the passage of the electric current.

In the construction herein shown, as has already been explained, the shanks of the binding-posts pass through the interior space of the cover. Consequently the coacting portions of the terminals require to be offset from the portions thereof which surround the said shanks and which are clamped to the cover by the nuts 14 and 15. In other cases, however, it may not be found necessary thus to offset the terminals.

I have made experiments with a view to devising a construction embodying a solder-joint that shall operate at a temperature only slightly exceeding the melting-point of the solder employed. The conditions present in a small and more or less delicate instrument of the class under consideration are somewhat unusual. The parts temporarily united by the solder-joint are necessarily under some degree of stress tending to separate them from each other; but it is desirable that such stress shall not be excessive, and it is essential that the device shall act absolutely without fail. It is also obvious that in spite of precautions taken to prevent the entrance of dust into the interior of the instrument there are certain unfavorable positions of use in which such entrance may occur. The dust may in time accumulate to so considerable a degree as to clog the mechanism and decrease the operative stress just mentioned. It is essential that the thermostat should act even under this adverse condition.

In the course of investigation I have found that when two metal plates are arranged face to face with a film of solder between them, forming a solder-joint, and this combination of parts is heated in a test-oven the metal plates separate at an earlier point of time when subjected to a moderate stress in the plane of their approximately contiguous surfaces than they do under the same stress applied in a direction normal to that plane. In other words, such metal plates slide apart sooner than they pull apart. I have further found that a very advantageous form for such metal plates is that of tubes, one of which is slightly smaller in diameter than the other, so as to slip into it with just clearance enough for the introduction of melted solder between the latter, forming an annular film or zone, adhering when cool to both of the tubes and preventing them from sliding or slipping upon each other. Such tubular form affords the maximum of strength and area of the metal pieces with the minimum of thickness thereof. A further step consists in closing the end of one of the tubes and utilizing the closed end as a bearing for the actuating part of the in-

strument which is to be normally held from motion, but released upon the melting of the solder-joint. The said closed end also admits of the use of a very thin tube by assisting in 5 stiffening the same.

In carrying the foregoing conceptions into effect I have arranged the instrument as follows: A central aperture is formed in the cap 2 to receive a sleeve 16 of hard rubber. The 10 inner end of the sleeve has an outwardly-turned flange 161 abutting against the interior rim of the aperture. The body of the sleeve projects outward through the aperture. The outer end of the sleeve has an inwardly-turned flange 162. A thin metal tube 17 constitutes one of the two parts between which the solder-joint is formed. The tube 17 has an outwardly-turned flange 171 at its 15 base, which overlies the flange 162 of the sleeve 16 and retains the tube within the sleeve, and a brass or other metal ring 172 is slipped upon the tube to strengthen the flange 171, inasmuch as the tube is likely to make a somewhat loose fit in the sleeve and is made of 20 such thin material that the said flange might "give" enough to allow the tube to become disengaged from the sleeve. Within the outer end of the tube is placed a slightly smaller tube 18, closed at its outer end, which may 25 conveniently be termed a "cap" and which constitutes the second of the two parts of the solder-joint. 19 designates the annular film or zone of solder between the tube and cap. After assembling the tube, ring, and cap it 30 is found most convenient to introduce the film of solder between the tube and cap by dipping the assembled parts into a receptacle of melted solder, and thereby applying a complete coating to them. In this way they are 35 completely protected from corroding without the sensitiveness of the instrument being in any degree decreased. The sleeve 16 serves to support the tube 17 and to insulate it thermally, so as to minimize dissipation of heat; 40 but obviously in some cases the whole cover 2 might be formed of hard rubber, and there would then be no necessity for the use of the separate rubber sleeve.

A retaining disk or saucer 21 is attached to 45 the under surface of the spring-terminal 14, and a spiral spring 22 is introduced, which takes bearing at its upper end against the saucer 21 and at its lower end against the closed end of the cap 18. The spiral spring 50 is arranged to force the spring-terminal out of electrical contact with the fixed terminal and into supporting contact with the base-plate. The parts are so proportioned that only a slight degree of motion is required in 55 order to bring the spring-terminal into this latter position, and thus only a moderate degree of angular deflection can by any possibility occur. The spiral spring 22 may be made stronger than is necessary to displace 60 the spring-terminal into its position against the base-plate, so as to insure the forcing out of the cap 18 when the zone 19 of solder

melts. Thus the instrument is maintained in its normal inactive state so long as the cap 18 and tube 17 are united by the interposed 70 film of solder.

The described construction, as has already been implied, affords the necessary strength of the parts that are united by the solder-joint, while permitting them to be formed 75 from very thin metal. Hence the heat that actuates the device has the most immediate access to the film of solder and the least opportunity of dissipation through surrounding parts. When the solder melts and the 80 cap is forced out of the tube by the pressure of the spiral spring, it will be seen that the movement of the cap is from a relatively cool part of the tube to a relatively hot part thereof, and there is therefore no tendency 85 for the solder to resolidify to any degree and so retard the complete and immediate escape of the cap.

Only a very small amount of solder, which is relatively an expensive material, is required in the device as thus constructed. The tubes and caps may be cheaply made 90 and easily assembled in large quantities.

I make no claim herein to the combination, in a thermostat, of means of support, terminals thereon, thermally-released mechanism normally operative to hold the terminals separated from each other, means to bring the terminals into contact with each other, and a coating fusible in the presence of abnormal heat applied to the contact portions of 95 the terminals.

What I claim is—

1. In an electric alarm, the combination of a base-plate, a cover, binding-posts mounted 105 on the cover, and shanks for such binding-posts passing through the base-plate and provided with nuts to hold the base-plate and cover together.

2. In an electric alarm, the combination of 110 a base-plate, a cover, projections on the base-plate making contact with the cover, the said base-plate, projections, and cover being provided with holes therethrough, and screws passing through such holes to attach the in- 115 strument to a fixed support.

3. In an electric alarm the combination of a base-plate, a cover, a thermal device projecting from the cover, screws passing through the base-plate and cover to attach the instrument 120 to any suitable support, and hollow plugs upon the screws to elevate the screw-heads above the surface of the cover and thereby protect the thermal device from injury.

4. In an electric alarm, the combination of a base-plate, a thermal device projecting therefrom, screws passing through the base-plate to attach the instrument to any suitable support, and hollow plugs upon the screws to 130 elevate the screw-heads above the thermal device and thereby protect the latter from injury.

5. In an electric alarm, the combination of

a base-plate, a cover, projections on the base-plate making contact with the cover, the said base-plate, projections, and cover having holes therethrough, screws passing through such holes to attach the thermostat to a fixed support, and a raised rim on the cover, surrounding the projections.

6. In a thermostat, the combination of a means of support, a terminal mounted thereon, a second terminal movable into contact with the first, and spring-pressed to tend to cause such movement, a fixed metal tube, a metal cap fitting the tube and united thereto by solder, and a connection between the cap and the spring-pressed terminal whereby the pressure of the said terminal constantly tends to separate the cap from the tube and operates to do so upon the solder becoming melted.

7. In an electric alarm, the combination of a base-plate, a cover, a spring-terminal mounted on the base-plate, a second terminal co-operating therewith, a thermally-released element supported by the cover, and a spring interposed between the latter element and the spring-terminal for holding the spring-terminal separated from its co-operating terminal and in supporting contact with the base-plate while the thermostat is set for operation.

8. In an electric alarm, the combination of a base-plate, a cover, a binding-post having a shank extending through the space between the base-plate and cover, a terminal formed integrally of spring metal having a recurved and offset end provided with an aperture to receive the said shank, and a nut on the said shank to secure the terminal in place.

9. In an electric alarm, the combination of a base-plate, a cover, binding-posts having shanks extending through the space between

the base-plate and cover, terminals consisting of plates having oppositely-offset supporting portions through which the shanks of the binding-posts pass, and nuts on the said shanks to secure the said plates in place.

10. In a thermostat, the combination of operating mechanism adapted to be held normally inactive, and a thermally-operated element composed of two parts united by a solder-joint, and a coating of solder completely covering the said parts.

11. In a thermostat, the combination of a means of support, terminals thereon, a cover inclosing the terminals, a thermal device supported by the cover, connections between the thermal device and the terminals, and an intermediate thermally-insulating member interposed between the cover and the thermal device to minimize dissipation of heat from the latter to the former.

12. In a thermostat, the combination of a means of support, a terminal mounted thereon, a second terminal movable into contact with the first, but normally restrained from such movement, a fixed metal tube, a metal cap fitting the tube and united thereto by solder, and a connection between the cap and the movable terminal including means of pressure constantly tending to separate the cap from the tube and to permit the movable terminal to make contact with the fixed terminal, and operating to do so upon the solder becoming melted.

In testimony whereof I affix my signature in presence of two witnesses.

LEONARD H. DES ISLES.
